UNITED STATES PATENT OFFICE.

SAMUEL T. WHITAKER, OF COLUMBUS, GEORGIA, ASSIGNOR OF FIFTY-ONE ONE-HUNDREDTHS TO RALPH B. SMALL, OF COLUMBUS, GEORGIA.

CRIMPED-BOTTLE-CAP REMOVER.

1,267,152.

Specification of Letters Patent.

Patented May 21, 1918.

Application filed December 18, 1915. Serial No. 67,659.

To all whom it may concern:

Be it known that I, SAMUEL T. WHITAKER, a citizen of the United States, residing at Columbus, in the county of Muscogee 5 and State of Georgia, have invented certain new and useful Improvements in Crimped-Bottle-Cap Removers; and I do hereby declare the following to be a full, clear, and exact description of the invention, such as 10 will enable other skilled in the art to which it appertains to make and use the same.

This invention relates to improvements in tools for removing crimped caps from bottles, and has for its primary object, the 15 reduction in cost of production and the reduction of space occupied.

With this and other objects in view as will in part be rendered obvious and in part be stated, the invention comprises certain 20 novel constructions, and combinations as will be subsequently rendered clear and thereafter specifically pointed out in the claims.

In the accompanying drawing,—

25 Figure 1 is an edge view of a tool embodying the features of the present invention and illustrated as disposed in the position assumed at the beginning of a bottle cap removing operation, a fragment of a 30 bottle and its cap being indicated in dotted lines.

Fig. 1^a is a similar view of the same not in its operating position.

Fig. 2 is a front elevation thereof.

35 Fig. 3 is a view similar to Fig. 2 of a modified embodiment.

Fig. 4 is an edge view of the tool seen in Fig. 3.

40 Fig. 5 is a front elevation of a further modified embodiment.

Fig. 6 is a longitudinal section taken on the plane indicated by line 6—6 of Fig. 5.

It is the common and well known practice to provide relative large, somewhat 45 cumbersome and proportionally expensive tools for removing crimped caps from bottles which necessitates the retention of such tool for repeated use, and perhaps most prominent among this type of tool is that form 50 made of thin sheet metal and cut with some form of notch in its edge to produce a hook like portion designed to engage the lower edge of the flange of the cap, a portion of the tool extending far enough to rest 55 edgewise on top of the cap. Economy has

demanded that such a tool be not discarded after first use but retained for subsequent use, and it is one of the objects of the present invention to produce a tool which will operate just as efficiently as the larger and 60 more expensive tools but which will be produced at such small cost that it may be once used and then thrown away, thus enabling the supplying of the tool with the bottles.

To this end the present improved tool is 65 formed of sheet metal making up a body 1, but the operating part is not notched into the edge of the body, but is produced by providing a hook shaped portion 2 stamped outward from the face of the body and 70 out of the material of the body in position for engaging the lower edge of a crimped cap, as clearly seen in Fig. 1. The end portion of the tool nearer the hook 2 is bent at 3 to space the body of the tool from and 75 engage the extremity of the tool upon the intermediate portion of the cap when applied, and for enabling retention of the tool in engagement with the neck of the bottle, and also for facilitating positioning the tool 80 at a desirable angle for removing a cap. The opposite end portion of the tool is also bent at 4 to conform to the shape of the neck portion of the body when carried by the neck, and also for holding the fingers to 85 facilitate manipulation of the tool.

In Figs. 3 and 4 is seen a modified embodiment consisting of exactly the same form of tool made up of the body 1' but differing slightly in being provided with 90 two hooks 2' instead of a single hook.

In Figs. 5 and 6 is seen a further embodiment wherein the body 1'' of the tool is formed with an elongated notch or slot ranging backward from the cap engaging 95 end of the tool, the material struck from the slot being bent into a cap-flange engaging hook 2''.

It is perfectly obvious that numerous other modifications may be produced, and 100 it will be noted that one of the essential characteristics of the structure resides in the fact that the hook member outstands laterally from the side of the flat tool.

What I claim is:—

1. A tool for removing crimped caps from bottles comprising a substantially flat strip bent transversely at one end to provide a bearing portion adapted to engage a cap and space the strip therefrom, and a hook 110

- portion stamped from the strip and extending substantially at right angles thereto in the direction of said bent end and being of a length equal approximately to the width 5 of the flange of the cap to be removed, said hook portion being spaced from the bent end sufficiently to dispose the bent end upon the central portion of the cap when the hook portion engages the flange of the cap.
- 10 2. A tool for removing crimped caps from bottles comprising a substantially flat body and an approximately hook shaped projection extending therefrom substantially at right angles to the planes of the

flat faces of the body, the cap engaging end 15 portion of the body being offset to cause the body to stand up slightly above the cap when the end portion thereof is engaging the same, and the hook shaped projection being proportioned to, during such engagement, extend beneath the edge of the cap. 20

In testimony whereof I affix my signature in presence of two witnesses.

SAMUEL T. WHITAKER.
